(Cl. D54—13)

To all whom it may concern:

Be it known that I, Frank Homme, a citizen of the United States, residing at Parshall, in the county of Mountrail and State of North Dakota, have invented a new, original, and ornamental Design for a Tire Tool or Similar Article, of which the following is a specification, reference being had to the accompanying drawing, forming part thereof.

Figure 1 is a side elevational view of a tire tool or similar article, showing my new design,

Figure 2 is a front elevational view,
Figure 3 is a rear elevational view,
Figure 4 is a top plan view, and
Figure 5 is a bottom plan view thereof.

I claim:
The ornamental design for a tire tool or similar article, as shown.

FRANK HOMME.
